(57) **CLAIM**

We claim the ornamental design for a food container, as shown and described.

DESCRIPTION

FIG. 1 is a perspective view of embodiment one, of a food container, in accordance with our new design;

FIG. 2 is an exploded perspective view of a food container of FIG. 1;

FIG. 3 is a top plan view of the food container of FIG. 1; FIG. 4 is front elevation view of the food container of FIG. 1;

FIG. 5 is a left side elevation view of the food container of FIG. 1;

FIG. 6 is a rear elevation view of the food container of FIG. 1;

FIG. 7 is a right side elevation view of the food container of FIG. 1;

FIG. 8 is a bottom plan view of the food container of FIG. 1;

FIG. 9 is a perspective view of embodiment two, of a food container, in accordance with our new design;

FIG. 10 is a top plan view of the food container of FIG. 9; FIG. 11 is a front elevation view of the food container of FIG. 9;

FIG. 12 is a left side elevation view of the food container of FIG. 9;

FIG. 13 is a rear elevation view of the food container of FIG. 9;

FIG. 14 is a right side elevation view of the food container of FIG. 9;

FIG. 15 is a bottom plan view of the food container of FIG. 9;

FIG. 16 is a perspective view of embodiment three, of a food container, in accordance with our new design;

FIG. 17 is a top plan view of the food container of FIG. 16; FIG. 18 is a front elevation view of the food container of FIG. 16;

FIG. 19 is a left side elevation view of the food container of FIG. 16;

FIG. 20 is a rear elevation view of the food container of FIG. 16;

FIG. 21 is a right side elevation view of the food container of FIG. 16; and,

FIG. 22 is a bottom plan view of the food container of FIG. 16.

The broken lines in the figures illustrate the portions of the design that form no part of the claimed design.
